HYDRAULIC DISPENSER FOR COLLAPSIBLE
TUBE CONTAINERS

Wallace M. Houldsworth, Royal Oak, Mich.

Application January 12, 1948, Serial No. 1,857

8 Claims. (Cl. 222—97)

1

This invention relates to a dispensing device and particularly to improvements in means for exerting pressure upon collapsible tubes containing semi-fluid or plastic material and controlling the discharge of the material therefrom.

An important object of this invention is to provide a novel means for dispensing the contents of collapsible flexible tubes, such as the conventional toothpaste and shaving cream containers or the like, which is simple in construction and operation and is inexpensive to manufacture.

Another important object of the invention is to provide a novel dispensing device of this character which may be incorporated as a part of the tube at the time of its manufacture or may be formed as separate unit capable of being assembled upon a conventional type of dispensing tube. Another important object of the invention is to provide a device of this character which is sanitary and economical in use and which serves to positively expel the desired amount of the content material from a tube in a manner which prevents any back and forth movement of the content material in the tube and also eliminates any possibility of breaking or cracking the tube. A further important object of this invention is to provide a novel dispensing plate adapted to be assembled upon a collapsible dispensing tube and exert a pressure thereon to force the material toward and through a novel dispensing control cap. A still further important object of this invention is to provide a novel cut-off cap capable of automatically functioning with a snap action to cutoff the flow of the content material and close the discharge opening of the tube.

In carrying out the invention, there is provided a key member which may be permanently affixed to the tube at the time of manufacture thereof to form a part of the sealing means thereof or can be attachably connected by the purchaser on the sealed end of a conventional dispensing tube. Associated with the key in a novel manner is an improved squeezing plate shaped so as to fit over the flattened sealed end of the tube either at the time of its manufacture or assembled thereon by the purchaser. Preferably associated with the key end squeezing plate is a novel form of cap for the dispensing tube which functions in cooperation with the squeezing plate to control the discharge of the content material from the tube. The discharge cap is provided with a novel spring means which enables the cap to automatically return to closing position with a snap action after manual pressure thereon has been released.

Various other objects, advantages and merito-

2

rious features of the invention will become more fully apparent from the following specification, appended claims and accompanying drawings wherein:

- 5 Fig. 1 is a perspective view of a dispensing tube having the elements of the present invention assembled thereon and showing in dotted outline one of the positions assumed by the squeezing plate and key.
- 10 Fig. 2 is an end view of the discharge end of the tube showing the cap in closed position thereon.
- 15 Fig. 3 is a longitudinal fragmentary sectional view taken along line 3—3 of Fig. 1, and
- 20 Fig. 4 is a side elevation of the discharge end of the device showing in section the cap thereon. Referring to the drawings, a dispensing tube which may be of the conventional type of toothpaste and shaving cream tubes is generally indicated at 10. One end of the tube 10 converges to form a neck 12 through which the content material is discharged upon squeezing of the tube. Mounted on the neck is an improved form of cap generally indicated at 14. The opposite end of the tube 10 is sealed as in conventional practice
- 25 and the stem of a key member indicated at 16 is constructed for engagement with the sealed end. The key member cooperates with a squeezing plate generally indicated at 18.
- 30 The stem of the key member 16 for the major portion of its length is of channeled formation and either may be slid over the sealed end of the tube 10 or can be clenched thereover at the time of the tube's manufacture. The key member is provided with a handle 20 on one projecting end thereof which may be turned or twisted by the user to wrap successive flattened portion of the tube thereabout and cause the advancement of the key and the squeezer plate toward the discharge end of the tube.
- 35 The squeezer plate 18 may be assembled on the tube at the time of its manufacture or later by the purchaser of the tube. The squeezer plate is generally in the form of a sleeve member comprising two converging side walls 22—22 corresponding in shape and formation to one another which act upon opposite sides of the dispensing tube upon which it is fitted. These wall sections are joined together by end walls 24—24 of corresponding shape and formation to one another.
- 40 The end walls extend at right angles to the tube engaging walls 22—22 and serve as bridging elements connecting the two side walls together. The squeezing plate 18 is preferably formed from
- 45 a material so that the side and end walls thereof

are integrally connected together into a unit. The end walls 24-24 are each provided with a relatively wide opening 26 through which both the sealed end of the tube and the key member 16 are inserted as shown in Fig. 1.

The converging side wall sections 22-22 terminate short of abutment as shown in Fig. 3 to form a narrow slot 27 through which the flattened sections of the tube extend. Each side section 22 adjacent to the slot 27 is provided with an outwardly turned flange or lip 28 extending the length of the slot and cooperating with the other lip to serve as a rest or support upon which the flattened wound portions of the tube will bear.

In the use of the squeezer plate the handle 20 of the key is rotated causing successive portions of the tube to be drawn through the slot and wound upon the key and thereby progressively advance the squeezer plate longitudinally of the tube. The winding action plus the squeezing pressure exerted by the advance of the wall sections 22-22 will exert a pressure upon the content material of the tube forcing the same toward the discharge neck 12.

The discharge neck 12 may have a spring member 30, preferably formed of either flat spring steel or round wire stock, which nearly encircles the neck 12 as shown in Figs. 1 and 4. The opposite ends of the spring are bent outwardly and may be curled upon themselves to form loops as shown at 32. One side of the neck 12 is provided with an outwardly projecting longitudinal ridge or boss 34 around which the spring fits when assembled thereon preventing said spring from turning movement.

The cap member 14 as shown in Fig. 4 is shaped with a convex spherically formed protuberance 36 which is received over a similarly formed rounded end or protuberance 38 on the outer end of the neck 12. The two protuberances 36 and 38 are of substantially the same radii holding the cap from sidewise or lateral movement but permitting the same to rotate.

Extending around the neck 12 immediately adjacent to the protuberance 38 is a widened shoulder 40 which cooperates with the cap 14 to hold the same from disengagement therefrom. Preferably the cap as shown in Figs. 1 and 2 is of square shaped formation, the mid-portions of the side edges thereof being closer to the neck than the corners thereof. The cap is provided with at least two side walls 42-42, which may be disposed diametrically opposite to one another, and which extend past the shoulder 40 formed on the neck 12. These side walls of the cap are inwardly turned as at 44 to extend in under the shoulder 40 to hold the cap snugly against the spherical radius of the protuberance 38. Preferably the cap is made of spring material so that the interned rounded flanges 44-44 resiliently hold the cap tight against the end of the tube. If desired a gasket may be interposed between the two convex portions 36 and 38 but if the neck is formed of soft metal or like material this may not be necessary.

The loops 32 of the spring member 30 are disposed under opposite corners 46-46 as shown in dotted outline in Fig. 2 and serve to resistingly hold the cap against rotation. When the cap is rotated by finger pressure from its initial closed position, each end wall 42-44 of the cap engages a loop 32 of the spring and thereafter the turning movement of the cap to open position is yieldingly resisted by the spring. When finger

pressure is released, the cap will automatically return to its starting closed position. The distance of rotation of the cap is limited preferably to approximately 90 degrees or less and for this purpose the ridge or boss on the neck may extend into one corner of the cap and for engagement with one of the walls 42 to limit the rotation of the cap.

The protuberance 38 of the neck is provided with a discharge opening 48 which may be of oval formation as shown. Likewise the convex portion 36 of the cap is provided with an oval shaped opening 50. Normally these openings are out of registration but when the cap is rotated 15 to discharge position the two openings come into registration allowing the content material of the tube to be discharged therefrom. This rotative movement, as previously described, is accomplished against the resistance of the spring 20 30, which upon release of the finger pressure applied will urge the cap to its initial starting position cutting off the flow of content material discharging through the opening 48 and sealing the discharge end of the tube.

25 During the winding of the key 16, the stem of the key comes in contact with one side edge of the opening 26-26 and in this manner the winding of the tube is started on substantially the longitudinal centerline of the filled portion 30 of the tube and in line with the center of the narrow slot 27. The kinking of the flattened portions of the tube as they are drawn through the narrow slot functions as a lock to hold the contents of the tube forwardly of the 35 slot under created pressure therein. The other side edge of openings 26-26 may be made large enough to enable the tube to be disassembled from the device after its contents are substantially used up.

40 The winding key may not only serve as the medium for rolling the tube upon itself and for advancing the squeezing body or plate 18 but also serve as a part of the sealing means for the closed end of the tube. As previously 45 mentioned, the key may be formed on the tube at the time of its manufacture and when so installed the channel shaped stem 16 may be permanently clenched to the closed end of the tube to seal the same.

50 As a result of this invention there is provided an improved device which operates in a hydraulic manner to progressively discharge the content material from a dispensing tube and which cooperates with an automatic cut-off cap for controlling the discharge of the content material. The automatic cut-off cap of this invention eliminates the necessity of employing engaging threads on the neck and cap as in conventional practice and exerting manual pressure to return 55 the cap to cut-off position. The combination of the spring 30 with its looped engaging ends 32-32 and the spherical engaging relation of the cap part 36 with the protuberance 38, provides a controlled rotatable movement of the cap 14 on the 60 axis of the tube.

What I claim is:

1. A device for attachment to collapsible dispensing tubes comprising, in combination, a body adapted to embrace and be mounted upon the tube for longitudinal movement therealong, said body including two side walls converging rearwardly of the tube and terminating short of one another to form a narrow transverse slot through which flattened portions of the tube may be drawn, a pair of flat plate elements bridging the

space between said side walls adjacent to the opposite ends thereof and connecting the side walls together into a unit, said plate elements projecting rearwardly from the side walls crosswise to the longitudinal axis of the slot and each provided with an enlarged recess opening into the slot, a key member extending through the recesses of the plate elements and rotatable therein, said key member adapted to engage the closed end of the tube and upon rotation to effect the rolling up of the tube on the key member to thereby draw flattened portions of the tube through the slot for the expulsion of the tube contents.

2. In combination with a collapsible dispensing paste tube closed at one end and having a discharge opening at the other end, a body adapted to embrace the tube and slide longitudinally therealong, said body including a pair of oppositely disposed side walls arranged angularly to one another and converging rearwardly of the tube, said side walls terminating short of actual convergence to form a transverse slot through which portions of the tube flattened by the side walls may be drawn, a pair of flat plate elements, one at each end of the slot, bridging the space between the side walls and connecting the same together for unitary action on the tube, said plate elements extending rearwardly of the side walls and crosswise to the slot and each provided with an enlarged recess rearwardly of the slot and opening thereto, a key member extending through said recesses of the plate elements and being channeled in formation for engaging the closed end of the tube, said key adapted upon rotation to effect the rolling up of the tube thereon to thereby draw the tube through the slot for the expulsion of the tube contents from the discharge opening at the other end of the tube.

3. In a device of the character described for attachment to a collapsible dispensing tube, a body designed to be mounted on and carried by the tube, a pair of side walls forming a part of the body and inclined angularly with respect to one another so that they converge rearwardly of the tube, said side walls terminating short of abutment to form a narrow transverse slot through which flattened portions of the tube may be drawn, a pair of plate members of corresponding shape and formation integrally secured to the opposite ends of said side walls and extending rearwardly of the tube, said plate members each provided with an enlarged recess disposed in line with said slot and opening thereto, a rotatable key member of channeled formation adapted to be clenched to the closed end of the tube and upon rotation to effect the rolling up of the tube thereon to draw flattened portions of the tube through the slot for the expulsion of content material from the opposite discharge end of the tube.

4. In combination with a collapsible dispensing tube closed at one end and having a discharge opening at the other end, a body embracing the tube and movable longitudinally therealong, said body including a pair of oppositely disposed side walls arranged in converging relation to one another and terminating short of actual convergence to form a narrow transverse slot through which portions of the tube flattened by the side walls may be drawn, an outwardly projecting lip secured to the inner edge of each side wall adjacent to said slot cooperating with one another to form a rest upon which flattened wound por-

tions of the tube may bear, one or more flat plate elements secured to the side walls and extending rearwardly thereof crosswise to the slot and around the closed end of the tube, said one or more plate elements each provided with an enlarged recess rearwardly of the slot and opening thereto, a key member extending through the recesses of said one or more plate elements and secured to the closed end of the tube, said key member adapted upon rotation to wind flattened portions of the tube drawn through the slot upon itself and to cause the wound portions to exert a forward thrust on said lips.

5. A device for attachment to a collapsible dispensing tube having one end shaped with a normally closed outlet for the discharge of content material therethrough and the opposite end sealed, said device comprising a pair of oppositely disposed side walls arranged in converging relation to one another such that the widely spaced ends of the walls are spaced apart sufficiently to receive a filled portion of the tube and such that the opposite ends of the walls terminate short of actual convergence to form a narrow transversely extending slot through which flattened portions of the tube are drawn, a rotary key member for connection to the sealed end of the tube and adapted upon rotation to wind successive flattened portions therearound, means connected to said side walls and carrying the key member therewith in trailing relation thereto as the side walls advance relatively toward the discharge end of the tube, and a lip connected to the end of each side wall forming the slot and projecting outwardly laterally away from the slot and extending along the slot substantially coextensive therewith, the two lips cooperating together to form a rest adjacent to the slot and upon which flattened portions of the tube wound by the key member may bear for exerting a forward thrust on the device.

6. A device for exerting squeezing pressure on a collapsible dispensing tube and movable longitudinally along the tube from the sealed end thereof toward the discharge end thereof as the content material is progressively expelled therefrom, said device comprising a pair of oppositely disposed side walls arranged in converging relation to one another such that the widely spaced ends of the walls are spaced sufficiently apart to receive a filled portion of the tube and such that the opposite end of the walls terminate short of actual convergence to form a narrow slot through which flattened portions of the tube are drawn, a pair of flat plate elements disposed at the opposite ends of the slot and extending rearwardly of the side walls and crosswise to the slot, each plate element having the forward portion thereof connected to the adjacent side edges of said converging walls and stiffening the side walls against outward expansion as the side walls exert a squeezing pressure on the tube, each plate element further having a recess therein rearwardly of the slot and opening thereto, a rotary key member engageable with the sealed end of the tube and adapted upon rotation to wind successive flattened portions of the tube therearound, said key member extending through said recesses of the plate elements and carried thereby in trailing relation to the side walls, and a lip connected to the end of each side wall forming the narrow slot and projecting outwardly laterally therefrom for substantially the full length of the slot, said lips cooperating to form a bearing surface on each side of the

slot for receiving the forward thrust imposed thereon by the successively flattened portions of the tube wound around the key member.

7. A device for a collapsible dispensing tube containing paste-like content material and having a non-removable cap secured to the discharge end of the tube and movable to open and closed positions, said device comprising a pair of oppositely disposed side walls arranged in converging relation to one another and with their outer side edges spaced apart approximately the same diameter of the tube, said side walls terminating short of actual convergence to form a narrow slot and each having a lip on its respective side of the slot extending laterally away therefrom and cooperating with the lip of the other side wall to form a rest, a pair of oppositely disposed end plate elements extending crosswise of the slot and connected to the converging side walls to stiffen the same against outward expansion, each end plate element having a recess therein wider than the slot and opening into the slot, a rotary key extending through the recesses of the end plate elements in substantially parallel relation to the slot and shaped to engage the sealed end of the tube, said key adapted upon rotation to wind the tube whereon flattening said tube as it is drawn through the slot, the winding of the tube creating a thrust against the rest forcing the device forward, thus creating a pressure within and forming a lock to hold the content material of the tube under such pressure, so that when the cap on the discharge end of the tube is moved to open position the content material will be automatically expelled from the tube.

8. A device for a collapsible dispensing tube containing paste-like content material and having a non-removable valve secured to the discharge end of the tube and movable to open and closed positions, said device comprising a pair of oppositely disposed side walls arranged in converging relation to one another, and with their outer edges spaced apart approximately the same diameter of the tube, said side walls terminating short of actual convergence to form a narrow slot, and each having a lip on its

respective side of the slot extending laterally away therefrom and co-operating with the lip of the other side wall to form a rest, a pair of oppositely disposed end plate elements extending crosswise of the slot and connected to the converging side walls and providing means against outward expansion thereof, each end plate element having a recess therein wider than the slot and opening into said slot, a rotary key extending through the recesses of the end plate elements in substantially parallel relation to the slot and shaped to engage the sealed end of the tube, said key adapted upon rotation to wind the tube thereon, while being wound the tube is flattened as it is drawn through the slot which creates a thrust against the rest forcing the device longitudinally forward, thus creating a hydraulic pressure within the tube and forming a lock to hold the content material of the tube under such hydraulic pressure, to be used for hydraulically expelling the content material from the discharge outlet of the tube when it is desired.

WALLACE M. HOULDSWORTH.
